United States Patent Office.

FREDERICK MENZER, OF SAN FRANCISCO, CALIFORNIA.

Letters Patent No. 101,489, dated April 5, 1870.

IMPROVED EXTENSION BED.

The Schedule referred to in these Letters Patent and making part of the same.

To all whom it may concern:

Be it known that I, FREDERICK MENZER, of the city and county of San Francisco, State of California, have invented an Improved Extension Bed with Drawers; and I do hereby declare the following description and accompanying drawings are sufficient to enable any person skilled in the art or science to which it most nearly appertains to make and use my said invention and improvements without further invention or experiment.

The object of my invention is to construct an improved extension bed, which shall be more especially useful as a bed for growing children, and where space is limited; and

It consists in making the bed with two sets of side rails, one set being attached to the head-board and the other set to the foot-board, and combining with this construction slats or supporters for the mattress, placed lengthwise and hinged together, at a point which enables a portion to stand perpendicularly against the head-board when the bed is closed up.

The mattress is also jointed, and, when the bed is closed up, may serve for a bolster, or it may stand entirely out of the way like the bottom.

Drawers are arranged at both head and foot of the bed, so as to close beneath it and out of sight.

Referring to the accompanying drawings—

A is the head-board, and B the foot-board of a bed. These may be plain or carved, as desired.

From the head-board the upper and lower side rails C and D extend as far as the shortest length intended for the bed, and are slotted, as shown at *a a*.

The rails E and F are attached to the foot-board and slide on the others, the upper rail E being tongued, so as to fit a corresponding groove in the rail C, while the rail F slides similarly within the rail D, as shown.

The rails C and D are united by bars *b b*, and the rails E and F by bars *c c*, so that they are steadied and caused to move together.

The bottom G is made of the same length as the rails C and D, and supports the extension-slats H. One end of the slats is fastened to the foot-board, and by its motion they are drawn out or closed. The other ends are jointed or hinged to this first part at *d*, so that, when the bed is to be shortened or closed, this head portion will stand at an incline or vertically within the recess *f* made in the head-board for the purpose.

In order to aid this portion in taking its position, an inclined strip, I, is placed so as to guide it, and, if the bed is only partially closed, this strip supports the head-slats and the mattress so as to form a bolster.

The mattress J is also jointed like the slats, and subjected to a similar motion and disposal when the bed is closed.

Beneath the bottom G are drawers K and L, which, when closed, are entirely concealed, and which serve to contain bedding and articles of clothing. The end of the drawer L forms a part of the foot-board, and operates with it.

By this construction I am enabled to produce a bed which will be suitable for a child, and can be extended when necessary. It is also very convenient when the room is small, as it can be closed during the day and extended at night.

Having thus described my invention,

What I desire to secure by Letters Patent is—

In combination with the double side rails C D and E F, the adjustable slats H, arranged to be employed as herein described.

In witness whereof I have hereunto set my hand and seal.

FREDRICK MENZER. [L. s.]
